(57) **CLAIM**

The ornamental design for a weighted training garment, as shown and described.

DESCRIPTION

FIG. 1 is a front view of a weighted training garment showing my new design.

FIG. 2 is a right side view showing my new design.

FIG. 3 is a rear view showing my new design; and,

FIG. 4 is a left side view showing my new design.

The broken line showing of a human head is for illustrative purposes only and forms no part of the claimed design. It is understood that broken lines within the weighted training garment indicate stitching lines.
